BIB

Jacob Goldberg, New York, N. Y.

Application April 22, 1935, Serial No. 17,669

1 Claim. (Cl. 2—50)

This invention relates to new and useful improvements in a bib.

The invention has for an object the construction of a bib which is characterized by a flat panel 5 of material, a band horizontally across the center thereof and releasably attached at one end and fixedly mounted at the other end, and a pair of straps from the shoulders of the panel attached to said band.

10 A feature of this construction is that the straps and band may be turned inside out relative to the panel of material so that the panel may be worn with either side to the exterior.

15 A further feature of the invention resides in the fact that the band and the pair of straps may be used as an efficient means by which to securely attach the bib on an infant.

20 The invention further contemplates forming the top edge of the bib with a neck cutout, arranging a binding strip along the neck cutout, and continuing this binding strip to constitute said pair of straps.

25 Another object of the invention is the construction of a modified form wherein the bib may be used with either the top or the bottom edges of the panel as the top thereof.

30 Still further, the invention proposes the construction of an article as described which is simple and durable and which can be manufactured and sold at a reasonable cost.

35 For further comprehension of the invention, and of the objects and advantages thereof, reference will be had to the following description and accompanying drawing, and to the appended claims in which the various novel features of the invention are more particularly set forth.

In the accompanying drawing forming a material part of this disclosure,—

40 Fig. 1 is a rear elevational view of a bib constructed according to this invention.

Fig. 2 is an edge elevational view looking from the right hand end of Fig. 1.

Fig. 3 is a horizontal sectional view taken on the line 3—3 of Fig. 1.

45 Fig. 4 is a rear elevational view of the bib shown in Fig. 1 turned with the outer side of the panel towards the rear thereof.

Fig. 5 is a rear elevational view of a bib constructed according to a further modification of 50 the invention.

The bib, according to this invention, comprises a flat panel of material 10 equipped with a band 11 extended horizontally across the front thereof and permanently attached at one end 11^a to one edge of the panel of material, and re-

leasably attached at the other end 11^b to the opposite edge of the panel of material. A pair of straps 12, and 13 extend from the shoulders of the panel 10 to the said band 11.

The panel of material 10 preferably should be 5 a material which may be used with either side constituting the outer side thereof. A strip of binding 14 is attached along the edges of the panel 10. The upper edge of the panel is formed with a neck cutout 15. Binding material 16 is attached along this neck cutout and continues and forms the straps 12 and 13. The extremities of the straps 12 and 13 are attached by stitches 18 to the center of the band 12. The end 11^a of the band is stitched to the edge of the panel of 10 material 10. The end 11^b of the band is equipped with a snap fastener element 17 engageable with 15 a complimentary snap fastener element 17' mounted upon the edge of the panel of material for releasably holding these parts together. 20

The end 11^b of the band may be detached and the bib easily engaged in place upon an infant by engaging it so that the head passes between the straps 12 and 13 and the arms above the band 11. The snap fastener elements 17 and 17' 25 may then be engaged to hold the bib in position.

In Fig. 4 the bib shown in Figs. 1-3 inclusive is illustrated in a reversed condition so that the original inner side of the panel of material 10 is now disposed to the outer side. The article is 30 placed into this condition merely by turning it inside out relative to the band 11 and the straps 12 and 13. With this accomplished, the snap fasteners 17 and 17' will be at the left and the band 11 will be permanently attached at the 35 right, as clearly illustrated on the drawing, contrasted with a reverse arrangement illustrated in Fig. 1. It will be readily seen that thus the bib may be worn with either side to the exterior. This is an advantage in that when one side of the 40 panel of material becomes slightly soiled it may still be used with the inner side placed to the outer side so that it has the appearance of a completely clean bib.

In Fig. 5 a modified form of the invention has 45 been disclosed wherein provision is made for using the bib with either the normally top or the normally bottom edges thereof arranged at the top. Furthermore, the bib may be used with either side of the panel of material to the outer side. More 50 particularly, the bib comprises a flat panel of material 10 formed with a neck cutout 15 at its normal top and a neck cutout 15' at its normal bottom. The edge of the material 10 is covered by a binding strip 14' sewed into position. A band 55

11' extends horizontally across the center of the material 10 and is permanently secured at one end 11^a and releasably mounted at the other end 11^b.

- 5 Snap fasteners 17 and 17' serve to form the releasable connection between the end 11^b of the strap and panel of material. A pair of straps 12' and 13' is permanently attached at one of their ends by stitches 18' to the center of the band 11'.
10 The other ends of the straps 12' and 13' are equipped with snap fastener and complementary snap fastener elements 20 mounted upon the ends of the straps and the top edge of the panel of material. The snap fastener elements on the 15 ends of the straps are also engageable with other complementary snap fastener elements 20' mounted upon the bottom of the panel of material. Thus, when the straps 12' and 13' are connected with the top edge of the material 10, 20 the operation of the device is similar to that previously described. If the top of the bib material becomes soiled it is possible to switch the straps 12' and 13' around so as to connect with the bottom of the bib material as indicated by the dot 25 and dash lines. The bib material may then be turned upside-down and used with the original bottom edge acting as the top edge.

The size of the bib may also be made larger to

form aprons. It may be used for any other purpose.

While I have illustrated and described the preferred embodiment of my invention, it is to be understood that I do not limit myself to the precise construction herein disclosed and the right is reserved to all changes and modifications coming within the scope of the invention as defined in the appended claim.

Having thus described my invention, what I 10 claim as new, and desire to secure by United States Letters Patent is:—

In a reversible bib, a substantially rectangular panel of material adapted to be used on both sides, the central portion of the top and bottom edges 15 being convexly curved to form neck bays, a waistband extending between the side edges of said panel, at least one end of said waistband being attached to one of said side edges, fastener elements upon said panel at each end of each neck 20 bay, a pair of shoulder straps attached to said waistband and extending to the ends of either of said neck bays and complementary fastener elements on the free ends of said straps, whereby the straps may be fastened to the top or bottom 25 edge of said panel.

JACOB GOLDBERG.
